UNITED STATES PATENT OFFICE

DANIEL F. TRACEY, OF HUNTINGTON, WEST VIRGINIA

SILENT FLUSHING APPARATUS

Application filed October 15, 1929. Serial No. 399,767.

Generically this invention relates to flushing tanks having a valve inlet and a siphon outlet and is primarily designed to effect the noiseless flow of fluid into the tank and likewise noiseless exhaust of the fluid therefrom.

One of the principal objects of this invention is the provision of a siphon and means coacting therewith to control the fluid exhaust from the tank through said siphon to effectuate its silent emptying and at the same time permit its refilling without continuous siphoning action.

A still further object of this invention is the provision of a siphon provided with a series of graduated perforations in its free extremity, a movable cup embracing said extremity, normally seating on the bottom of the tank but movable to contact the open end of said siphon and seal the same when the water has receded to a predetermined point, said air inlet perforations and cup coacting with said siphon to effectuate the noiseless emptying of the tank.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a longitudinal section of the tank and closure therefor and the movable cup and valve, with siphon and valve control mechanism in elevation and showing movement of the latter in dotted outline.

Fig. 2 is a bottom perspective view of the tank closure.

The flush tanks and operating mechanisms with which I am familiar have proven deficient, in that the siphoning action is attended by considerable noise which is likewise true of the refilling operation; further deficiencies being that such fluid inlet control mechanisms comprising a valve actuated arm having a ball mounted on its free end adapted to follow the water level in either ascending or descending direction often through wear and tear becomes out of plumb in its

line of travel, either causing a valve leakage or binding against the wall of the tank thereby preventing the valve from completely closing, or from deterioration requiring frequent replacement, such leakage not only being inherently undesirable but effecting considerable noise in addition to that attendant upon the normal filling of the tank; likewise the siphoning action in emptying the tank in such devices produces an undesirable noise, and it was to overcome the deficiencies of such devices, and to provide an inlet valve control mechanism positive in operation, comprising a valve control trigger coacting with said arm to actuate the valve in closing direction at predetermined intervals during the refilling of the tank to control the fluid flow to effect the noiseless filling of the tank, said weighted arm adapted to normally maintain said valve in closed position, and means coacting with said arm for moving said valve to open position; and a siphon for emptying said tank formed with an air inlet tube and graduated perforations in its free end normally surrounded by a movable cup, said air inlet perforations and cup coacting with said siphon to slow up the siphoning action as the water level reaches predetermined points in emptying direction to effect a noiseless siphoning action during emptying of the tank, that I designed the device forming the subject matter of this invention.

In the illustrated embodiment characterizing this invention there is shown a tank A, a closure therefor B, an inlet valve control mechanism C, and a siphon mechanism D, and which will be more fully hereinafter described under the respective headings "Tank structure", "Valve control mechanism", "Siphon mechanism", "Operation", and "Conclusion".

Tank structure

The tank A, in the present instance of rectangular configuration, is formed with sides including 1 and 2, and bottom 3 provided with an opening 4 adapted to receive an outlet conduit hereinafter described and an opening 5 adapted to receive an inlet conduit as hereinafter more fully appearing.

The tank A is provided with a closure B conforming in configuration to that of the tank and formed on its under surface with a vertically depending flange 6 spaced from the end and side edges of said closure to form lateral flange 7. Said flange 7 is adapted to seat on the ends and side walls of tank A, and the flange 6 is adapted to extend within the tank and snugly engage the inner surfaces of said sides and ends to provide a substantially air tight container and to constitute an air chamber 8. Substantially central of one side of the closure, said flange extends inwardly at right angles to the edge of the closure and then parallel with the flange of the opposite side and outwardly to form a recess chamber 9 adapted to receive the upper end of the siphon when the closure is operatively positioned, and is formed with an air outlet aperture 10, for a purpose herein-after more fully appearing.

Valve control mechanism

A valve mechanism E, controlling the flow of water into the tank is formed with a tubular section 11 adapted to extend through opening 5 for suitable connection with an inlet conduit, not shown, said section being formed with an annular chamber 12, provided with outlet openings 13 in its bottom wall 14, a valve stem 15 mounted in the upper portion of said tubular member 11 with its lower end 16, of larger diameter than the member 11, seating on bottom 14 to cut off or permit flow of fluid through said member 11 into chamber 12 as desired. Integrally formed on tubular member 11 above chamber 12 are lips 17 between which are mounted on pin 18, toe portion 19 of valve operating arm 20, said toe extending through opening 21 of tubular member 11. The free end of said toe 19 is adapted to extend within a suitable opening in valve stem 15 for vertical reciprocation of said stem, as shown by dotted lines. Arm 20 is normally adapted to rest in a perpendicular position and terminates at its upper end in T-member 22, which is formed with a longitudinal bore adapted to slidably receive one end of rod 23, the other end of said rod having ball member 24 suitably secured thereon, said rod 23 being secured in any desired adjusted position by thumb screw 25, as will be apparent without further description.

An L-shaped support arm, apertured to register with opening 5 is adapted to seat on bottom 3, secured in any suitable manner to the side 1, and is formed with an apertured projection 26 to which is hingedly secured trigger member 27, by pin 28. The central portion of said trigger 27 is cut out to provide slot 29 and rearwardly projecting finger 30, formed at its free end with downwardly extending catch 31. The lower wall of slot 29 is formed with an upwardly projecting catch

32, adapted to engage pin 33 of arm 20 when the latter is moved to position shown in dotted lines. Said pin 33 is adapted to successively engage the catches 32 and 31 to effect an intermittent actuation of valve 16 as the water level reaches a predetermined point in tank filling direction as will hereinafter more fully appear. A laterally extending lug 34 is suitably formed on or secured to the free end of arm 27, threadedly apertured to receive stem 35 of float 36, suitably mounted on the upper end thereof.

It is apparent that actuation of stem 35 in projection 34 will effect vertical adjustment of said stem and float with respect to trigger 27. However, if desired, float 36 may be adjustably mounted on said stem to effect adjustment of trigger 27 with respect to a predetermined water level point.

While the weight of ball 24 will normally retain the valve 16 in closed position through the instrumentality of arm 20, yet, in order to effect positive sealing of said valve in cases of extra high water-pressure, a lock arm 37, terminating at its upper end in weight 38, and its lower end in branch fingers 39 and 40, respectively, the said arm 37 extending at an angle with respect to said branches and pivotally mounted substantially central of its length, on pin 41 suitably mounted in the rear side of tank A, extending to the exterior thereof, and suitably keyed or otherwise secured to the free end of said pin 41 is operating handle 42. The said ball or weight 24 is formed on its upper surface with a horizontal seat portion 43, adapted to be normally engaged by finger 39 to fixedly maintain the said ball 24 in valve closing position. The latter is also formed with a lug 44, normally positioned between said fingers 39 and 40 and adapted to be engaged by finger 40 upon actuation of handle 42 to effect movement of arm 20 to the position shown in dotted outline to effect opening of valve 16, as will hereinafter appear.

Siphon mechanism

The said siphon D is adapted to be mounted within the reservoir or tank A with its lower end 45 extending through opening 4 in bottom 3 for connection with the bowl or element to be flushed, as will be clear without further description. The upper or bent end of said siphon is adapted to extend above the normal water line and into recess or air outlet chamber 9, and inlet pipe 47 is adapted to have one end communicating with the top of the short leg of siphon D as at 48, and extends downwardly parallel with said leg to a predetermined point, with its open end in the present instance substantially central of the tank A, as at 49. Adjacent to its lower or inlet end siphon D is formed with a series of spaced, graduated openings 50, 51 and 52 respectively. While these openings may be

varied according to the exigencies of the particular requirements, in the present instance, they are graduated so that 52 is $\frac{1}{16}$ ", 51 is $\frac{1}{8}$ ", and 50 $\frac{15}{16}$ ", which operates to control the admission of air to said siphon for a purpose hereinafter to appear.

5 A metallic cup 53, with its bottom diameter substantially the same as that of siphon D, and its open end of greater diameter, is 10 adapted to seat on bottom 3 and to embrace the free end of said siphon member with its upper edge normally extending slightly above the uppermost opening 52, so that as long as the cup is filled with water said opening is sealed, as will be more fully apparent 15 from the operation of the device.

Operation

While the operation of this device would 20 seem to be clear from the above description, it might be well to go into further detail as to the coordination of the components forming the subject matter of my invention, and by means of which the noiseless filling and 25 exhausting of the tank is effected.

Assuming that the tank is filled to normal 20 water level as at 54, actuation of handle 42 will effect engagement of finger 30 with lug 44, and will give sufficient impetus to weight 30 24 aided by the opening of valve 16 to impel the arm 20 to the position shown in dotted outline, thereby opening the valve 16, whereupon the pin 33 will engage catch 32, and maintain said valve in open position.

35 As the water rises above the normal water line air will be expelled through opening 10 in chamber 9, but the air in chamber 8 will be trapped, thereby effecting a quick rising of the water level above and around siphon 40 D, which will start the siphoning action of the latter, and as the water level recedes or drops, the float 36, through the instrumentality of arm 35, will lower trigger 27, while weight 24 will move arm 20 to effect engagement of pin 33 with catch 31, thereby partially closing valve 16, with a consequent decrease in the flow of water into the tank; when the water level has reached the open 45 end 49 of air inlet 47, a sufficient amount 50 of air will be drawn into the siphon to slow up the siphoning action but not completely stop it, and when said level recedes to its predetermined low water level cup 53 will be drawn upward to seal the bottom opening 55 of the siphon D and as the water is exhausted from the cup, a small amount of air will be admitted through opening 52 which will tend to effect a further slowing up of the siphon, and a greater amount through 51, 60 which will effect its still further slowing up, and through opening 50, to completely stop said siphon.

As the water level rises in the tank, float 36 will elevate the trigger 27, releasing pin 65 33 from catch 31, whereupon weight 42 will

slowly move arm 20 to its original perpendicular position to completely close valve 16 by the time the water reaches its normal water level, 54, and float 36 its initial position. It is apparent that the cup 53 will remain in 70 its elevated position until the water nearly reaches the extremity 49 of pipe 47, at which point it will be filled, causing it to drop back to its initial position on the bottom 3.

It will thus be seen by initially permitting 75 full volume inflow of valve 16, and when the water has reached a predetermined level, partially closing the said valve, the inrush of water during the entire filling of the tank will be prevented and a noiseless filling of 80 the tank will thereby be effected, and that by virtue of air chamber 9, a quick submerging of the siphon is effected, greatly reducing the time and amount of water necessary to effect the starting of the siphon and by the 85 co-action of the siphon inlet 47, openings 50—52, and cup 53, a graduated control for the admission of air into the siphon and a consequent slowing up of the siphoning action effects the noiseless exhaust of the tank 90 contents as will be apparent from the above description.

Conclusion

From the above, it is apparent that I have 95 designed a flush tank apparatus, comprising an inlet valve mechanism, operable noiselessly to fill the tank, and a siphon device to noiselessly effect the exhausting of the tank, capable of long and continuous hard 100 usage, simple in construction, manufactureable at a reasonable cost and efficient for the purposes intended.

It will likewise be observed that I have 105 designed a silent flushing tank apparatus including a novel tank structure, and an inlet valve mechanism and siphon device for effecting the noiseless filling and exhausting of the tank, so correlated that the water will be exhausted from the tank and the inflow, 110 while quickly filling the same, will not reach the siphon before it is emptied, thereby prematurely starting the siphoning action as is prevalent in flushing devices now in use.

Although in practice I have found that the 115 form of my invention illustrated in the accompanying drawings and referred to in the above description as the preferred embodiment, is the most efficient and practical; yet realizing the conditions concurrent with the adoption of my invention will necessarily vary, I desire to emphasize that various minor changes in details of construction, proportion and arrangement of parts, may be resorted to within the scope of the appended 120 claims without departing from or sacrificing 125 any of the principles of this invention.

Having thus described my invention, what 130 I desire protected by Letters Patent is as set forth in the following claims:

1. A silent flushing tank comprising a reservoir, a closure for said reservoir, said closure constituting an air trapping chamber and an air outlet chamber, a source of water supply, a valve mechanism controlling the water supply, means for operating the valve mechanism, a siphon device for exhausting the reservoir, and means in connection with the device for silencing the exhaust, said means including air inlet means adjacent the open end of said siphon device, and air inlet means located central of the tank for effecting siphonic retardation in advance of said first mentioned air inlet means.
- 5 2. A silent flushing tank comprising a reservoir having an open end, a closure for said open end, said closure formed with a flange providing an air trapping chamber and an air outlet chamber, said flange constituting a closure securing means and effecting an air-tight connection between said trapping chamber and tank, a valve mechanism controlling the supply to the reservoir, means for operating the valve mechanism, a siphon device for exhausting the reservoir, and means in connection with the device for silencing the exhaust, said means including air inlet means adjacent the open end of said siphon device, and air inlet means located central of the tank for effecting siphonic retardation in advance of said first mentioned air inlet means.
- 10 3. A silent flushing tank comprising a reservoir having an open end, a closure for said open end including an air outlet chamber and an air compression chamber, a source of water supply, a valve mechanism controlling the supply to the reservoir, means for operating the valve mechanism, a siphon device for exhausting the reservoir, having its upper end extending within the air outlet chamber, air inlet means, including a series of openings adjacent its lower end, and a cup member embracing said lower end and movable to contact with same, whereby quick starting of the siphon and silencing of the exhaust is effected.
- 15 4. A flush tank of the character described comprising a tank, a closure therefore, means for supplying water thereto, a siphon exhaust, means for admitting air to said siphon so as to silence the same, and means in connection with the closure for rapidly accelerating the rise of the water as it approaches the upper end of the siphon to effect rapid siphonic action, an air inlet means located central of the tank for effecting siphonic retardation in advance of said first mentioned air admission means.
- 20 5. A flush tank of the character described comprising a tank, a closure therefore, means for supplying water thereto, a siphon exhaust, means for admitting air to said siphon in gradually increased volume so as to silence the same, and air compression means in connection with the closure for rapidly accelerating the rise of the water as it approaches the upper end of the siphon to effect rapid siphonic action, an air inlet means located central of the tank for effecting siphonic retardation in advance of said first mentioned air admission means.
- 25 6. A flush tank of the character described comprising a tank, a closure therefore, means for supplying water thereto, a siphon exhaust, means for admitting air to said siphon in gradually increased volume adjacent its open end, and additional means coacting with said air admitting means adapted to seal said lower end and effect silencing of the exhaust, and means in connection with the closure for rapidly accelerating the rise of the water as it approaches the upper end of the siphon to effect rapid siphonic action, an air inlet means located central of the tank for effecting siphonic retardation in advance of said first mentioned air admission means.
- 30 7. A flush tank of the character described comprising a tank, a closure therefore, means for supplying water thereto, a siphon exhaust, means for admitting air to said siphon in gradually increased volume adjacent its open end, and additional means coacting with said air admitting means adapted to seal said lower end and effect silencing of the exhaust, and means in connection with the closure for rapidly accelerating the rise of the water as it approaches the upper end of the siphon to effect rapid siphonic action, an air inlet means located central of the tank for effecting siphonic retardation in advance of said first mentioned air admission means.
- 35 8. A flush tank of the character described comprising a tank, a closure therefore, means for supplying water thereto, a siphon exhaust including an air inlet device, a series of graduated air inlet openings adjacent its open end, a tapered cup means embracing said open end coacting with said openings and movable to contact the bottom and lower exterior surface of said siphon to seal said lower end and effect silencing of the exhaust, and means in connection with the closure for rapidly accelerating the rise of the water as it approaches the upper end of the siphon to effect rapid siphonic action.
- 40 9. A silent flushing tank comprising a reservoir, a closure for said reservoir including an air compression chamber and an air outlet, a source of water supply, means for controlling the water supply, and a siphon device for exhausting the reservoir, whereby when the water in tank filling direction reaches said chamber air will be compressed therein causing the water to quickly raise around the upper end of said siphon to start the siphoning action and effect rapid exhausting of the reservoir, and means in connection with the device for silencing the exhaust, said means including air inlets adjacent the open end of the siphon, and air inlet means located central of the tank for effect-
- 45 100 105 110 115 120 125 130

ing siphonic retardation in advance of said first mentioned air inlets.

10. A silent flushing tank comprising a reservoir, a closure for said reservoir, means for supplying water to said reservoir, siphon means for exhausting the reservoir, and air compression means in connection with said closure, whereby when the water has reached a predetermined point in tank filling direction it will be restricted and accelerated in rising direction about the upper end of said siphon to effect quick starting of the siphoning action and effect rapid exhausting of said tank, and means for silencing the exhaust, said means including air inlets adjacent the open end of the siphon, and air inlet means located central of the tank for effecting siphonic retardation in advance of said first mentioned air inlets.
- 15 20. This specification signed this 23 day of September, A. D. 1929.
